CLAIM

The ornamental design for a plate-type antenna, as shown.

DESCRIPTION

FIG. 1 is a front elevational view of my new antenna;
FIG. 2 is a rear elevational view of my new antenna;
FIG. 3 is a side elevational view of the antenna taken
from the right of FIG. 1;

FIG. 4 is a top plan view of the antenna; and
FIG. 5 is a bottom plan view of the antenna.
